DOOR LOCK ATTACHMENT

Joseph Dominguez, New York, N. Y.

Application September 24, 1938, Serial No. 231,470

13 Claims. (Cl. 70—145)

This invention relates to door locks and more particularly to a door lock attachment provided with movable locking bolts to supplement the usual night latch for doors.

5 Doors to apartments and the like are generally provided with a single night latch at a point about half way up on the door. A type of night latch commonly used for doors to apartments includes a knob-like handle adapted to be turned 10 from the inside of the apartment to latchingly lock the door, and which, when so latched, renders the key actuatable mechanism non-responsive to the insertion of a key from outside the door. This type of latch lock has the advantage 15 that the tenant may not be disturbed against his wish while within his apartment by those possessing duplicate or pass keys. Such a single latch, however, has not prevented intruders from breaking into apartments whether locked from 20 the inside or by a key from the outside. For example, intruders desiring to force a door having a single lock have done so by merely inserting a tool between the door and door frame whereby they are able to spring the door sufficiently to 25 force the single latch and thus gain entrance into the apartment.

Attempts, heretofore, have been made to overcome the ineffectiveness of a single bolt night lock by providing doors with a plurality of locking bolts spaced at different points around the edge of the door. In order to render such locking bolts operable simultaneously to lock and unlock the door, complicated interconnecting and latching mechanisms were provided. Locking devices of this character, however, have not heretofore met with wide commercial success for the reason that their cost when compared with the cost of simple night latches have been regarded by would be purchasers as prohibitive.

30 An object of the present invention, therefore, is to provide a simple, cheap and easily applied locking attachment for a door having the usual night latch whereby additional locking bolts may be provided for the door at a small cost to the tenant.

35 Another object of the invention is to provide a novel attachment knob having parts provided with surfaces adapted to tightly grip the small knob or knob-like handle commonly provided on the usual night latch without substitution or modification of the night latch or any part thereof.

The above and other objects and advantages of the invention will become more apparent upon 40 consideration of the following detailed descrip-

tion and the appended claims when read in connection with the accompanying drawing, in which:

Figure 1 is an inside view of a door fitted with the lock attachment of the present invention, 5 parts being broken away for convenience of illustration;

Figure 2 is an end view of one form of an attachment knob with parts broken away to show the gripping elements thereof in operative position;

Figure 3 is a cross-sectional view taken on line 3—3 of Figure 2;

Figure 4 is a plan view of the gripping elements;

Figure 5 is an enlarged sectional view taken on line 5—5 of Figure 1;

Figure 6 is an enlarged view of an adjustable rod connection shown in Figure 1 with a part thereof in section;

Figure 7 is a cross-sectional view of a modified form of attachment knob taken on line 7—7 of Figure 8; and

Figure 8 is a cross-sectional view of the same form of attachment knob as viewed along line 8—8 of Figure 7.

Referring to Figure 1 of the drawing, a door 10 and door frame 12 are shown provided with the usual night latch 14 with a form of the novel lock attachment of the present invention applied thereto. Additional locking bolts 16 and 17 which are preferably case hardened or otherwise made to withstand the cutting effect of saw teeth are shown located at the upper and lower edges of the door 10. Each bolt is provided with a 35 guiding bracket 18 and a receiving bracket 19 secured to the door and door frame respectively. Secured to the knob-like handle 20 of the night latch 14 is an attachment knob 22. While the knob-like handle 20 is shown in Figures 2, 3 and 40 5 as being of elliptical shape, it will be readily apparent that the form of attachment knob 22 illustrated in Figures 1 to 4 is adapted for attachment to circular, rectangular and other shaped knobs as well.

45 The attachment knob 22 comprises a hollow circular body 23 adapted to receive the small knob-like handle 20 of the night latch, a pair of clamping elements 24 and 25 being provided to grip and hold the small knob within the body 23. Gripping elements 24 and 25 are of arcuate shape as viewed in Figure 4, each having an inner transversely arcuate surface 26 and 27, respectively, particularly adapted to fit about the rear side portions of the usual elliptically shaped 50 55

knob 20, but which will also obviously grip other shaped knobs with equal effectiveness. Cap screws 28 and 29 extend through the crown portion of the hollow body 23 and threadably engage gripping elements 24 and 25. When the attachment knob 22 is placed over a small latch knob 20 and the arcuate shaped elements 24 and 25 drawn inwardly against the rear side portions of the small knob by turning cap screws 28 and 29, the elements 24 and 25 operate to effectively grip and tightly clamp the small knob 20 against the crown portion of the attachment knob.

The arcuate gripping elements 24 and 25 are each provided with a pin at one end thereof for pivotal connection with rods 30 and 31 which in turn are connected to upper and lower bolts 16 and 17 respectively. Each of these rods include an adjustable connection 32 whereby the lock attachment is adapted to be readily applied to doors of different size when the location of the usual night latch is considerably varied with respect to the height of a door. Adjustable connections 32 are formed as shown in Figure 6 by providing rod sections 30a and 30b with rack-like teeth 34 over an appreciable length thereof. Sleeves 33 and 37 are provided for each connection to hold the rod sections thereof in any desired adjusted position. Each sleeve has a spring lip 38 adapted to engage the rack teeth on one of the rod sections so as to retain the sleeve in adjusted position over the end of the other coacting rod section.

When one desires to lock the door, all that need be done is to turn attachment knob 22 which operates to simultaneously actuate in addition to the single bolt of night latch 14, the locking bolts 16 and 17, the usual inner spring (not shown) of the night latch 14 being effective to hold the bolts in their extreme locking position. The bolts 16 and 17 are received in brackets or recesses 19 at the upper and lower edges of the door, and together with the bolt of latch 14 operate to provide a three-point locking engagement for the door. Any one attempting to break or force the latch lock 14 coupled with the locking attachment of the present invention will thus be unsuccessful since he will be unable to spring the door either from the top or bottom thereof.

To unlock the door, the knob 22 is, of course, turned in the reverse direction, thus withdrawing bolts 16 and 17 from receiving brackets 19, and at the same time unlocking night latch 14. The usual inner spring of the night latch, previously described, also functions to hold the locking bolts in their extreme unlatched position.

While the latch lock 14 and the bolts 16 and 17 are in locked position, no one will be able to force entrance either with a key or jimmy tool, and the tenant in possession thereof may be assured the privacy and security afforded by more expensive locking equipment.

Another form of attachment knob of the present invention is illustrated in Figures 7 and 8, comprising a hollow body 40 having in the rear wall thereof an elliptically shaped opening 41 for the reception of a similarly shaped knob-like handle. The ledge portions 42 and 43 of the hollow body adjacent the long sides of the elliptically shaped opening 41 are provided with diametrically opposed arcuate-shaped recesses 44 and 45, respectively. When an elongated or elliptically shaped handle or knob 20 is received through the opening 41 and turned through an angle of 90°, the ends of the handle will come into engagement with the recesses 44 and 45. To firmly

hold the handle on the ledges 42 and 43 the cap portion of the attachment knob 40 is provided with a set screw 48, adapted to engage and tightly clamp the handle within the arcuate recesses 44 and 45. Pins 50 and 51 are provided on the rear wall of the knob 40 adjacent ledges 42 and 43 for pivotally mounting rods 52 and 53 for connection with locking bolts 16 and 17 similarly as illustrated in Figure 1.

While two specific forms of the invention have been illustrated, other forms embodying the principles of the invention will be readily apparent. It should therefore be understood that the forms of the invention herein described and shown in the drawing are to be regarded as illustrative only of typical embodiments of the invention and not as limiting the scope thereof.

I claim:

1. In a lock attachment for doors provided with a lock having a handle for the inside of the door and means movable by actuation of said handle for locking the door; the combination of a movable bolt adapted to be located at a distance from said locking means, a hollow attachment knob of a shape and size adapted to fit onto and conceal said handle, and to provide a gripping surface for manual actuation thereof, means for securing said knob to said handle, and means operatively connecting said bolt to said knob for positive actuation with said locking means. 30

2. In a lock attachment for doors provided with a lock having a handle for the inside of the door and means movable by actuation of said handle for locking the door; the combination of a movable bolt adapted to be located at a distance from said locking means, a hollow attachment knob, means for clamping said handle within said knob, and means operatively connecting said bolt to said knob for actuation with said locking means. 40

3. In a lock attachment for doors provided with a lock having a handle on the inside of the door and means movable by actuation of said handle for locking the door; the combination of a movable bolt adapted to be located at a distance from said locking means, an attachment knob, members having arcuate-shaped surfaces for gripping and holding said handle for movement with said knob, and means operatively connecting said bolt to said knob for actuation with said locking means. 50

4. In a lock attachment for doors provided with a lock having an elongated handle and means movable by actuation of said handle for locking the door; the combination of a movable bolt adapted to be located at a distance from said locking means, an attachment knob provided with a pair of members each having an arcuate-shaped surface adapted to engage the rear side portions of said elongated handle, means for clamping the handle against the arcuate surfaces of said members to secure said knob thereto, and means operatively connecting said bolt to said knob for actuation with said locking means. 60

5. In a lock attachment for doors provided with a lock having an elliptically shaped handle and means movable by actuation of said handle to lock the door; the combination of a movable bolt adapted to be located at a distance from said locking means, a hollow knob having an elliptically shaped opening adapted to receive said handle, means for clamping said handle within said knob at an angle to the major axis of said opening, and means operatively connect- 70 75

- ing said bolt to said knob for actuation with said locking means.
6. In a door lock having means operable by a key from the outside of the door for locking the door and a handle on the inside of the door operable to move said locking means and render same non-responsive to said key; the combination of an auxiliary lock attachment comprising a slidable bolt or bolts adapted to be located adjacent an edge of the door at a distance from said locking means, a hollow knob adapted to receive said handle, means for securing said knob to said handle, and means operatively connecting said bolt or bolts to said knob for boltting and unbolting the door upon actuation of said knob.
7. In a lock attachment for doors provided with a lock having a handle for the inside of the door and means movable by actuation of said handle for locking the door; the combination of a movable bolt adapted to be located at a distance from said locking means, an attachment knob, means for securing said knob to said handle, and means operatively connecting said bolt to said knob for actuation with said locking means, said connecting means including a pair of rod-like sections adjustable for shortening and lengthening said connecting means throughout an appreciable portion thereof and means for holding said sections together in adjusted position.
8. An attachment knob of the character described comprising a hollow body having an opening adapted to receive a small knob-shaped handle, said body including means having arcuate-shaped handle-gripping surfaces, and means for tightly clamping a handle against said arcuate-shaped surfaces.
9. An attachment knob of the character described comprising a body adapted to fit adjacent a small knob-shaped handle, means including arcuate-shaped surfaces adapted to engage the rear side portions of the handle, and means associated with said body for tightly clamping said arcuate-shaped surfaces to the handle.
10. An attachment knob of the character described comprising a hollow body adapted to receive a small knob-shaped handle, a pair of handle-gripping elements each including an arcuate surface adapted to engage the rear side portions of the handle, and means including screw threads for drawing said elements into said body to tightly grip the handle therein.
11. An attachment knob of the character described comprising a hollow body having an elongated opening adapted to receive elongated knob-like handles, a pair of ledges adjacent the long sides of said opening, and means for clamping and holding an elongated handle against said ledges for movement with said body.
12. The attachment knob as defined in claim 11 said ledges being recessed to grippingly receive the ends of the elongated handle.
13. An attachment knob of the character described comprising a hollow body having an elliptically shaped opening for the reception of similarly shaped handles, ledges defining the long sides of said opening provided with arcuate-shaped recesses adapted to receive and grip the ends of a handle, and a set screw in the crown portion of said body adapted to engage and clamp the handle in the recesses of said ledges.

JOSEPH DOMINGUEZ.
